United States Patent Office

Des. 194,184
Patented Dec. 4, 1962

194,184

BUILDING SCREEN WALL

Gordon J. Clauss, 2705 Katherine St., Fort Myers, Fla.

Filed July 21, 1961, Ser. No. 66,009

Term of patent 14 years

(Cl. D18—2)

Fig 1

Fig 2

FIG. 1 is a front elevational view of a building screen wall, embodying my new design;

FIG. 2 is an enlarged perspective view of one of the blocks shown in FIG. 1.

I claim:

The ornamental design for a building screen wall as shown.
